W. H. WINTERROWD,

DRAFT GEAR CARRIER FOR RAILWAY LOCOMOTIVES.

APPLICATION FILED FEB. 24, 1915.

1,257,437.

Patented Feb. 26, 1918.

UNITED STATES PATENT OFFICE.

WILLIAM H. WINTERROWD, OF MONTREAL, QUEBEC, CANADA.

DRAFT-GEAR CARRIER FOR RAILWAY-LOCOMOTIVES.

1,257,437.

Specification of Letters Patent. Patented Feb. 26, 1918.

Application filed February 24, 1915. Serial No. 10,371.

To all whom it may concern:

Be it known that I, WILLIAM H. WINTERROWD, residing in the city of Montreal, Province of Quebec, Dominion of Canada, have invented certain new and useful Improvements in Draft-Gear Carriers for Railway Locomotives; and I do hereby declare that the following is a full, clear, and exact description thereof:

10 My invention has for its object to adapt the usual draft gear of railway locomotives to be removed and replaced at will without dismemberment of the gear proper; and it may be said briefly to consist of a combined 15 footplate and draft-gear-receptacle rigidly secured between the ends of the frame or other rigid parts at the front and rear of the locomotive, and readily removable means serving to lock the draft gear proper within 20 the receptacle, the whole being so constructed and arranged that the draft-gear proper may be removed from or inserted into the receptacle at will.

For full comprehension, however, of my 25 invention reference must be had to the accompanying drawings forming a part of this specification, in which similar reference characters indicate the same parts, and wherein;

30 Figure 1 is a part plan view and part horizontal section of my combined foot plate and draw gear receptacle.

Fig. 2 is a part elevation, part vertical sectional view thereof, section being frequent- 35 tary and taken on line B B of Fig. 1.

Fig. 3 is a transverse sectional view taken on line A A Fig. 1.

40 Figs. 4 and 5 are enlarged detailed views of the means preventing displacement of the drawgear Fig. 5 being partially in horizontal section taken on the irregular line C C Fig. 4.

Fig. 6 is a vertical sectional view taken on the irregular line M M Fig. 3; and

45 Fig. 7 is a detail elevation illustrating a modification of the means illustrated in Figs. 4 and 5.

The principal member of my invention consists of a combined footplate and draft-gear-receptacle comprising a casting 2. This 50 receptacle is formed with a longitudinal chamber 5 of rectangular cross-section, and the forward end of the member is extended in depth by both upward and downward extensions 7 and 8 respectively, as shown in Fig. 3, the entire length of the member being 55 extended laterally in both directions as at 9

and 10 respectively, reinforced at its thickened forward end by top webs 12, and a web 13 at about midway the depth of the casting, each lateral extension presenting a sidebar 16 adapted to bear upon the locomotive frame and having a vertically disposed shoulder 4 adapted to engage a shoulder on such frame. The casting is secured to the locomotive frame by bolts 30 which pass through the side bars 16, the frame 3 and brackets 17 located on the opposite sides of the latter in transverse alignment with the casting. The rear end of the carrier is cast with a pair of relatively heavy bars 14 serving as a reinforcement against which the rear follower abuts when the draft spring is compressed and, in addition, accommodating the usual yoke or draft bar 15. The reinforced forward end, including its lateral extensions, 75 constitutes the footplate, shocks upon which are transmitted through the shoulders 4 to the frame of the locomotive.

The shoulders 4 are located slightly to the rear of the webs thus correctly positioning the footplate relatively to the frame of the locomotive. This reinforced footplate portion of the casting is formed with a rectangular opening 20 communicating with the interior of the receptacle, and a pair of vertical openings 116 extend through the top reinforced portion 7, the lower reinforced portion 8 having a relatively diminished opening (20°) of rectangular form.

The draft gear proper is located within 90 this carrier and for purposes of illustration the well known Sessions type is shown. This type comprises a pair of follower plates, 20 and 21, slidably fitted within the chamber 5, one at the inner end thereof and the other 95 adjacent to the openings 116. Between these follower plates are located the side and center friction blocks 24, 25 and 26 respectively and spring bar 23 within which the double coil draft spring 50 is located, the shank being indicated at 16 and yoke at 15.

The draft gear is adapted to be inserted bodily into my combined footplate and draft-gear-receptacle member where it is retained against displacement by a pair of 105 wedges or pins 35 dropped through the footplate into the seats 116. These wedges or pins are of sufficient width to overlap the front follower plate in close proximity to the shank 16, and they are reinforced by integral 110 outward extensions 36, the upper ends thereof being formed with heads 37 of the nature

of either a yoke, as shown in Fig. 4, uniting the two wedges together and serving as a handle, or individual handles, as shown in Fig. 5. The portions 126 or the casting 6 directly beneath a portion of the opening 116 (see Fig. 6) are made solid and with a flat top to have shoulders 127 on the wedges or pins rest thereon, while the openings 20^a are contiguous thereto and accommodate the 10 lower diminishing ends 136 of the wedges or pins. The handles extend above the top of the member and facilitate the withdrawal of the wedges or pins.

What I claim is as follows:

- 15 1. The combination with a pair of spaced engine frames, of a unitary member comprising a foot-plate and draft-gear-carrying portions, means rigidly securing the said unitary member between the engine frames 20 with the outer face of the member and outer ends of the frames in the same transverse plane relatively to the engine, for the purpose set forth.
- 25 2. The combination with a pair of spaced engine frames having outwardly facing shoulders, of a unitary member comprising a foot-plate and draft-gear-carrying portions, such means having shoulders for engagement with the shoulders on the frames, 30 and means rigidly securing the said unitary member between the engine frames with the outer face of the member and outer ends of the frames in the same transverse plane relatively to the engine, for the purpose set forth.
- 35 3. The combination with a pair of engine

frames of a foot-plate member located entirely between the frames and bolted thereto with its forward face flush with the forward ends of the said engine frame-parts, 40 such member being constructed and arranged to present a receptacle for a draft-gear, a draft-gear mounted in said receptacle and removable in the same horizontal plane in which it is located during service; 45 and detachable means retaining the draft-gear in place.

4. The combination with a pair of rigid parts of a locomotive frame, of a foot-plate member located entirely between the said parts and bolted thereto with its forward face flush with the forward ends of the said engine frame-parts, such member being constructed and arranged to present a receptacle for a draft-gear and the said member having a substantially flush top and forward reinforcement and openings intersecting the receptacle, a draft-gear mounted in said receptacle and removable in the horizontal plane in which it is located in service and means dropped into the openings and constructed and arranged to retain the draft-gear in place, the said means being united by a yoke serving as a handle, for the purpose set forth. 65

In testimony whereof I have signed my name to this specification in the presence of two witnesses.

WILLIAM H. WINTERROWD.
